UNITED STATES PATENT OFFICE.

CHARLES A. DAYTON, OF PRESTON, CONNECTICUT.

ELECTRIC STOP-MOTION.

SPECIFICATION forming part of Letters Patent No. 451,649, dated May 5, 1891.

Application filed April 21, 1890. Serial No. 348,867. (No model.)

To all whom it may concern:

Be it known that I, CHARLES A. DAYTON, a citizen of the United States, and a resident of Preston, in the county of New London and State of Connecticut, have made a certain new and useful Improvement in Electric Stop-Motions for Engines, which improvement is fully set forth and described in the following specification, reference being had to the accompanying sheet of drawings.

This invention relates to stationary steam-engines, and has for its object the production of a simple and inexpensive attachment to be used in connection with the speed-governor for the purpose of stopping said engine from distant parts of the shop. In cases of accident to employés or of breaking of machinery throughout the shop this is especially desirable. With my present invention the pressing of a button is the only action necessary to stop the engine and its connected machinery.

To explain said invention I have provided the annexed drawings, in which—

Figure 1 is a side elevation of a portion of an engine-bed, showing cylinder, steam-chest, governor, &c., and having connected thereto my electric stop-motion. Fig. 2 is a top view, somewhat enlarged, of the shaft and pulley which drive the governor and the system of levers and electro-magnet by means of which I am able to stop the engine, as hereinafter explained. Fig. 3 is an enlarged end view of one of the cut-offs that control the steam as it enters the cylinder; and Fig. 4 is a detail view, partly in section, of the connection between the governor and the rods for operating the valve-controlling mechanism.

In the drawings, the letter *a* denotes a portion of the engine-bed; *b*, the steam-chest; *c*, the governor as a whole; *d*, a lever hung on bed *a*, and *e* a rod connecting said lever with an eccentric on the crank-shaft of the engine, all of the described parts being substantially the same as in horizontal engines of the well-known Harris-Corliss class. The taking and exhausting of steam are controlled in the manner usual in such engines and, briefly described, consists of a disk *f*, that is located at the center of the steam-chest *c* and is rocked by a rod *g*, that connects said disk with the upper end of lever *d*. At the two upper corners of the steam-chest are rock-shafts *h*, that

carry valves which control the entering steam, and at the two lower corners are similar rock-shafts *i*, that control the exhaust. These several valve rock-shafts bear crank-arms *h'* and *i'*, the latter of which are connected with disk *f* by rods *k*.

The inlet-valve rods *h* bear crank-arms *h'*, that are connected with disk *f* by rods *k'*, in such manner that when the desired quantity of steam has entered the cylinder, rod *k'* is disengaged from the crank-arm *h'*, which is then quickly moved to close the connected valve.

On the valve-shafts *h* are disks *m*, that may be rocked by rods *n*, connecting with the governor, which disks are formed with projecting portions *m'*, that when rocked in either direction serve to disconnect the ends of rods *k'* from the crank-arms *h'* in a manner well-known in this class of engines. The raising or lowering of the governor-balls brings the projections *m'* into operative engagement with a latch on the ends of rods *k'*, this latch mechanism being best illustrated in Fig. 3 of the drawings.

On the end of connecting-rod *k'* is pivoted a fork, whose curved upper arm *o* as it advances engages and is forced downward by one of the projections *m'*. This depresses the lower arm *o'* of said fork and throws its hook-shaped end out of engagement with the arm *h'*. All of the elements thus far described are old and well-known to those skilled in the art, and I make no claim to them.

The mechanism which embodies my invention is connected with the pulley *p*, by means of which the governor *c* is driven. This pulley I make as a friction-clutch pulley of any practical form. As here shown it consists of two cup-sections, one fitting over the other in such manner that when the two sections are forced together the frictional contact of their engaging surfaces is sufficient to rotate the governor and its connected parts. The journal of the outer or longitudinally-movable section of said pulley is mounted in a lever-arm *q*, one of whose ends is hinged to a bracket *s*, attached to a rigid portion of the engine-bed. The other or free end of said lever is connected by a link *s'* with a lever-arm *t*, whose end nearest the friction-pulley is hinged in a bracket *t'*. The free end of lever *t* is

pressed outward by a spring u , secured to the engine-bed.

v denotes a pawl pivoted in the said bed and having its end formed as a hook that may 5 engage and hold the free end of lever t against the force of spring u . This pawl v also serves as the armature of an electro-magnet w , whose wires run to push-buttons located at convenient points in the shop.

- 10 The action of my described mechanism is as follows: When button x is brought into use and the electric circuit completed, the magnet w draws the hook end of pawl v out of engagement with the free end of lever t , 15 and said lever is then forced outward by spring u , carrying with it the connected lever t . The outer section of the friction-pulley is thus moved out of engagement with its companion section and the governor stops. As 20 the governor-balls drop, rods n are moved by means of the three-armed lever n' and rock the disks m and bring the projections m' into the path of the curved arm o of the fork with this result: the lower arm o' of said fork cannot 25 act to open the valves, and the engine, after two or three revolutions, stops. When it becomes necessary or desirable to again start the engine, lever t is forced inward against spring u and held in place by hook- 30 ing its free end under the pawl v , when the

engine is again in shape to run precisely the same as if my stop-motion were not applied thereto.

While I have described in detail my preferred construction of said stop-motion, certain modifications could be made therein without departing from the spirit of my invention, so long as the stop-motion is arranged to work with the governor in substantially the manner described. 35

I claim as my invention—

1. The combination, with the driving-shaft of an engine-governor, of electrically-operated mechanism, substantially as herein set forth, for throwing said governor out of working engagement with said engine, for the purpose specified. 45

2. In an engine, in combination with the driving-shaft of the governor, a clutch-pulley on said shaft, a system of levers connected with said pulley, as set forth, and an electro-magnet whose armature serves as a latch to control said levers to hold the two sections of the said clutch pulley in operative engagement, all being substantially as and for the 55 object specified.

CHARLES A. DAYTON.
